UNITED STATES PATENT OFFICE.

JOHN B. HEET, OF TRENTON, ILLINOIS; ANNA E. HEET ADMINISTRATRIX OF SAID
JOHN B. HEET, DECEASED.

SOCKET FOR SCAFFOLD TRESTLES.

Application filed January 14, 1926. Serial No. 81,234.

It is customary to use transverse pins or similar devices for holding the legs of a trestle to a transverse supporting bar or tie members between the legs, or both, acting to prevent the legs from separating incident to the weight upon the transverse bar. Some constructions use socket members for the legs, the socket members being also fastened to the transverse bar with anti-spreading means between the socket members (which receive the legs), thereby preventing the socket members from separating. These constructions are weak and it is necessary to retain the various parts of the trestle assembled at all times, rendering it very inconvenient for the trestle to be portable from one place to another.

The present invention has for its purpose to provide a socket member for scaffold trestles which does away with holding pins, screws and anti-spreading devices and yet at the same time enable the legs to be easily and very quickly disassembled from the socket member, allowing the various parts of the trestle to be arranged in a small compass either for storage or for transportation from one place to another.

It is another purpose to provide a socket member for scaffold trestles which may be constructed of relatively heavy sheet steel or in the form of castings and which are substantial in every respect and at the same time will prevent spreading of the legs of the trestle, it being possible to disassemble the two members of each socket member and remove the transverse bar and the legs, allowing the various parts to be transported in small compass.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in perspective of one end of a scaffold trestle, showing the improved socket member as applied and constructed in accordance with the invention.

Figure 2 is a vertical sectional view on line 2—2 of Figure 1.

Figure 3 is a transverse sectional view on line 3—3 of Figure 2.

Figure 4 is a detail view in perspective of the inner member of each socket member, and

Figure 5 is a detail view in perspective of the outer member.

Referring to the drawings, 1 designates a cross bar of a trestle and 2 denote socket members, one for each end of the cross bar. Each socket member may be constructed in any proportions and shape and may be made of suitable sheet steel or in the form of castings. Each socket member comprises an inner shell and an outer shell, the latter fitting over the former and fastened together.

The inner shell 3 comprises the side walls 4 which converge upwardly and terminate in lateral flanges 5. Connecting the side walls are end walls 6 which are notched or recessed, as shown at 7, for the reception of the ends of the cross bar or beam 1. The lower portions 8 of the end walls assist in withstanding the weight of the cross bar or beam and such work as may be supported thereby.

The outer shell or section also comprises side walls 9 which converge upwardly corresponding to the walls 4 but it will be noted that the outer shell or section is wider, that is, from one wall 9 to the opposite wall 9, than the inner section or shell, thereby causing to be formed leg receiving sockets 10. In this way, the legs 11 diverge downwardly. The outer section or shell also has end walls 12 somewhat similar to those of the inner section or shell and are recessed at 13.

The recesses 13 are of the same proportions as the recesses 7 of the inner section or shell and register therewith and also receive the ends of the cross bar or beam 1. The lower portions 14 of the end walls register with the lower portions 8 of the inner section or shell and assist the portions 8 in withstanding the weight of the cross bar or beam and such work as may be supported thereon.

The end walls of the inner and outer sections are riveted or otherwise secured together, as at 15 and 16. The latter fastenings connect the lower portions of the end walls while the former secure the upper portions of the end walls on opposite sides of the beam or bar 1. The outer section of the shell is a little different in construction

than the inner section or shell in that it has a top wall 17 which overlies the upper edge of the beam or bar 1 and also cooperates with the lateral extensions or flanges 5 to 5 withstand the pressure of the upper ends of the legs while engaged in their sockets.

Upon examination of the above in connection with the drawings, it will be understood that the operator, when through using 10 the trestle, may remove the legs from the sockets, withdraw the cross bar or beam, and then the several parts may be arranged close together in small compass, allowing the parts to be easily transported from one place 15 to another without any inconvenience, such as would be the case if the trestle remained assembled.

It will be noted by this construction of 20 socket member for scaffold trestles that nails, screws, braces such as tie chains and tie rods, and like devices are entirely eliminated. This construction of socket member for trestles enables the workman to very 25 quickly and easily assemble the parts when the same are to be used, it being noticed that

they may be disassembled with equal facility.

The invention having been set forth, what is claimed is:

In a scaffold trestle, a transverse work 30 supporting beam and supporting legs associated therewith and downwardly divergent therefrom, a casing removably connected to the end of the beam and provided with spaced sockets corresponding divergently 35 with the legs and adapted to removably receive their upper ends, said casing consisting of inner and outer sections, and means for fastening the sections together, one within the other, the inner side walls of the sockets having at their upper ends lateral extensions 40 or flanges which, together with the top walls of the outer section, resist the pressure of the upper ends of the legs, whereby the trestle may withstand the weight of the 45 work resting thereon.

In testimony whereof he affixes his signature.

JOHN B. HEET.
